UNITED STATES PATENT OFFICE.

CHARLES H. SAMPSON, OF ROCHESTER, NEW YORK.

DESIGN FOR A CASING FOR CHECK-PROTECTORS.

46,604.

Specification for Design.

Patented Oct. 27, 1914.

Application filed March 13, 1914. Serial No. 824,557. Term of patent 14 years.

To all whom it may concern:

Be it known that I, CHARLES H. SAMPSON, a citizen of the United States, residing at Rochester, in the county of Monroe and State of New York, have invented a new, original, and ornamental Design for a Casing for Check-Protectors, of which the following is a specification, reference being had to the accompanying drawing, forming part thereof.

Figure 1 is a top view of the casing for check protectors; Fig. 2 is a front elevation

of the casing for check protectors; Fig. 3 is a right hand side elevation showing my design; and Fig. 4 is a left hand side elevation showing my design.

I claim:

The ornamental design for casing for check protectors, as shown.

CHARLES H. SAMPSON.
